UNITED STATES PATENT OFFICE.

GLENN H. CURTISS, OF HAMMONDSPORT, NEW YORK, ASSIGNEE, BY MESNE ASSIGNMENTS, TO CURTISS AEROPLANE AND MOTOR CORPORATION, OF BUFFALO, NEW YORK, A CORPORATION OF NEW YORK.

VALVE-OPERATING SYSTEM.

1,284,250.

Specification of Letters Patent. Patented Nov. 12, 1918.

Application filed December 11, 1914. Serial No. 876,715.

To all whom it may concern:

Be it known that I, GLENN H. CURTISS, a citizen of the United States, residing at Hammondsport, in the county of Steuben and State of New York, have invented certain new and useful Improvements in Valve-Operating Systems, of which the following is a specification.

The valve mechanism of my invention is particularly adapted for use in connection with internal combustion engines having dual admission and exhaust valves. Upon an understanding of my invention however, it will be readily perceived that there are features of it which may be utilized with advantage in engines of other types. The aim of my invention is to attain a maximum degree of simplicity and reliability of operation of the dual valves and at the same time retain a cylinder head construction giving admission and exhaust chambers of ample size and of a form readily cooled and free from such irregularities of structure as may restrict unduly either the admission or the exhaust.

I arrange the valves in the head of the cylinder in pairs according to their character and dispose the valves of each pair symmetrically with respect to an axial plane of the cylinder. In the axial plane is provided a common valve rod and lever for one pair of valves, while lying without that plane and symmetrically disposed with respect to it I provide independent valve rods and levers for the valves of the other pair. The valve levers of this latter pair are mounted pivotally on a bridge structure which overlies the valves of the first named pair, and the valves of the first named pair are operated from a common lever by means of a T-head connected with the trunk of said lever and which engages both the said first named valves below the crown of the said bridge. The admission and exhaust are distributed symmetrically with respect to said axial plane.

Of the drawings Figure 1 is a top plan view of the cylinder of an internal combustion engine in which my invention is embodied;

Fig. 2 is a side elevation taken endwise of the cam shaft; and

Fig. 3 is a similar view at right angles to the cam shaft.

The various parts are referred to by the reference numerals by which they are designated upon the drawings.

(10) The cylinder proper. This cylinder is illustrative only, since any form of combustion chamber may be used. As usual the cylinder head proper is below the top, and the admission and exhaust chambers at the top. None of these chambers are shown but generally speaking the admission and exhaust chambers are divided from each other on a line A B.

(11, 11) The admission conduits to the admission chamber. These are symmetrically disposed with respect to the axial plane indicated by the lines C D in Figs. 1 and 3. Gas is fed to the admission chamber through each of these conduits.

(12) The exhaust outlet. This extends across the entire side of the cylinder, and as will be noted is of generous proportions. It is symmetrically disposed with respect to the plane C D.

(13, 13) A pair of exhaust valves symmetrically disposed with respect to plane C D. The stems of these valves (which are of the puppet type) are approximately vertically disposed. Other forms of valve may be substituted and their position changed at will just so that the symmetry with respect to plane C D is retained.

(14, 14) A pair of admission valves also symmetrically located with respect to plane C D. Their character and position as illustrated are both the same as those of the valves 13. Similarly both the character and position may be changed without affecting the symmetry.

(15, 16) Valve operating rod and lever respectively for operating the pair of admission valves 14. The valve rod is operated from a suitable cam shaft as usual. The valve lever 16 is pivoted intermediate its ends on a bracket rising from the top of the cylinder 10.

(17) A taper pin passed transversely of the trunk of lever 16 and constituting a T-head the opposite ends of which engage simultaneously the valves 14. This pin is preferably of steel, while the trunk of the T-lever thus formed may be of some softer cast metal. The pin 17 is secured by a nut on one end as indicated, the nut drawing it into its tapered socket in lever 16.

(18) A bridge structure overlying the admission valves 14 and comprising a pair of outlying brackets rising from the cylinder head and an interconnecting shaft constituting the crown of the bridge.

(19, 20) 19', 20') Synchronously operating pairs of valve rods and levers arranged to individually engage and operate exhaust valves 13. The levers 20, 20' are pivoted 10 on the crown shaft of the bridge 18 which shaft constitutes their pivotal axis. The rods 19, 19' are arranged in the same plane as the valve rod 15.

What I claim is:

15 1. In an internal combustion engine, a cylinder having a plurality of valves symmetrically arranged in its cylinder head, a single valve operating lever pivotally mounted on said head for operation in an 20 axial plane of said cylinder and actuating one set of said valves and a pair of separate levers also pivotally mounted on said head for movement in planes parallel to but on opposite sides of the plane of the first named 25 lever and individually actuating another set of said valves.

2. In an internal combustion engine, a cylinder having a pair of exhaust valves disposed in its head and operable by separate 30 levers, said levers being actuated by separate valve rods and both said levers and said rods being disposed in planes located on opposite sides of the axis of the cylinder, a pair of intake valves also disposed in said cylinder 35 head and substantially in line with said planes, a pair of inlet conduits, said valves being disposed intermediate said conduits, and a single lever in combination with a single valve rod mounted for movement in 40 the axial plane disposed between the aforesaid planes to simultaneously operate said intake valves.

3. In an internal combustion engine, a cylinder having a pair of intake valves and 45 a pair of exhaust valves in its head, said valves being arranged symmetrically of an axial plane passing through the cylinder, a single lever pivotally mounted upon said head for movement in an axial plane disposed between said exhaust valves and actuating said intake valves, a bridge structure mounted above the level of the pivotal point 50 of said lever, and a pair of levers carried by said bridge and disposed on the opposite

sides of said single lever for operation in planes parallel to the plane of actuation thereof and individually actuating said exhaust valves.

4. An internal combustion engine comprising a cylinder, dual admission and exhaust valves associated therewith, and arranged in pairs, a bridge across the valves of one pair, operating levers for the valves of the second pair pivoted thereon and operating in synchronism, and a third valve 60 lever intermediate the aforesaid pair of levers commonly operating the valves of the first named pair of valves and engaging them below the crown of the bridge.

5. An internal combustion engine comprising a cylinder, a pair of puppet valves of like character associated therewith and a common valve operating lever therefor having a T-head formed by inserting a taper pin transversely of the trunk of the lever. 70

6. In an internal combustion engine a cylinder having dual admission and exhaust valves arranged in pairs according to their character and symmetrically disposed with reference to an axial plane of the cylinder, 80 a valve operating rod and lever for one pair of said valves located in said axial plane, and individual operating valve rods and levers for the valves of the other pair symmetrically disposed with reference to said 85 plane.

7. In an internal combustion engine, a cylinder, dual admission valves therefor symmetrically located with respect to an axial plane, a valve operating lever and rod 90 located and operating in said plane, and a pair of admission conduits located on opposite sides thereof.

8. In an internal combustion engine, a cylinder, valves entering the cylinder, a lever to similarly operate a pair of said valves, an actuating rod for the lever, levers pivoted above the first said lever to operate other of said valves and actuating rods for each of the last said levers arranged in the 100 plane of the first said rod.

In testimony whereof I affix my signature in presence of two witnesses.

GLENN H. CURTISS.
